UNITED STATES PATENT OFFICE.

WILLIAM NEWTON BEST, OF LOS ANGELES, CALIFORNIA, ASSIGNOR TO
JOHN H. BEST AND EZRA BEST, OF QUINCY, ILLINOIS.

HEATING-FURNACE.

No. 806,628.

Specification of Letters Patent.

Patented Dec. 5, 1905.

Application filed March 30, 1905. Serial No. 252,865.

To all whom it may concern

Be it known that I, WILLIAM NEWTON BEST, a citizen of the United States, and a resident of Los Angeles, in the county of Los Angeles 5 and State of California, have invented a new and Improved Heating-Furnace, of which the following is a full, clear, and exact description.

This invention relates particularly to improvements in furnaces for annealing portions 10 of armor-plate where holes are to be drilled, for heating patches of metal, so that the same may be readily bent to form a perfect fit, and also for brazing and other purposes where intense heat is required, the object being to provide a furnace for the above-mentioned purposes 15 that may be conveniently handled and in which a low or cheap grade of fuel may be quickly volatilized—such fuel, for instance, as water-gas tar, coke-oven tar, crude oil, or 20 residuum oil, that are not so easily volatilized as gasoline, coal-tar, or naphtha.

I will describe a heating-furnace embodying my invention and then point out the novel features in the appended claims.

Reference is to be had to the accompanying drawings, forming a part of this specification, in which similar characters of reference indicate corresponding parts in all the figures.

Figure 1 is a longitudinal section on the 30 line 1 1 of Fig. 3 of a heating-furnace embodying my invention. Fig. 2 is a top plan thereof. Fig. 3 is a rear end view, and Fig. 4 is a section on the line 4 4 of Fig. 1.

The furnace comprises a casing 5, consisting 35 of any suitable metal, and arranged in the casing is a lining 6, of a refractory material—such, for instance, as fire-brick. The refractory material has a longitudinal opening 7, the inlet end 8 of which is contracted, as is also 40 the outlet end 9. Supported on a bracket 10 at the inlet end of the furnace is a burner comprising an oil-discharge 11, having connection with a source of supply through a flexible tube 12, and arranged adjacent to the 45 oil-discharge 11 is an air or steam supply nipple 13, connecting with a flexible tube 14. The object in contracting the end of the opening adjacent to the burner is to bring the refractory material as close to the burner as 50 possible, so that the said refractory material will be heated to a very high temperature and serve as an igniting brick or lining for the volatile gases, and as the gases expand in the chamber or opening of the furnace this taper

or contracted portion provides a resistance, so 55 that the fire does not force its way out of the burner end. The object in contracting the outlet end is to provide an impact which causes an abrasive heat upon a limited space, such as is required in annealing armor-plate. By 60 numerous experiments I have found it necessary to effect the highest possible efficiency from the fuel, especially in annealing armor-plate, that vents be provided, one being just inward of the beginning of the tapered outlet, as indicated at 15, and the other vent 16 65 is at the extreme end of the furnace.

The furnace is comparatively small and may be readily handled by a man. For convenience I provide it with a removable handle 17 and 70 suspend it so that it may be easily moved from place to place by means of a chain 18, adjustable in a yoke 19, having link connections 20 with the furnace. At the outlet end of the furnace is a peep-hole 21, through 75 which the nature of the flame from the burner may be observed.

In the operation for annealing a spot in armor-plate the outlet end of the furnace is to be held against the plate, as clearly indicated in Fig. 1. The two vents 15 and 16 will permit of the heat which is given off from the refractory material, as well as the heat caused by consumed volatile gases, to be forced by the atomizer of the burner against 80 the armor-plate. As the low-grade oil discharges from the part 11 of the burner it will be met by compressed air or steam from the nipple 13 and thoroughly atomized. It will be understood that the heat of the refractory 85 material assists combustion, as well as increases the heat from the burner.

Having thus described my invention, I claim as new and desire to secure by Letters Patent

1. A heating-furnace comprising a refractory material having a longitudinal opening, the ends of the opening being contracted, the said furnace having a vent near the outlet end and also a vent at the extreme end, and means for introducing a heat-producing agent at the 90 inlet end.

2. A heating-furnace comprising a refractory material having a longitudinal opening, the ends of the opening being contracted, the said furnace having a vent near the outlet end 95 and also a vent at the extreme end, and a hydrocarbon-burner supported at the inlet end of the furnace.

3. A heating-furnace comprising a metal casing, a lining of refractory material therein and having a longitudinal opening the ends of which are contracted or tapered, a vent inward of the outlet end, a vent formed at the end of the outlet portion, a hydrocarbon-burner at the inlet end, and an adjustable suspending device for the furnace.

In testimony whereof I have signed my name to this specification in the presence of two subscribing witnesses.

WILLIAM NEWTON BEST.
